UNITED STATES PATENT OFFICE.

ANDREW JOHN FREDRIKSON, OF JÖNKÖPING, SWEDEN.

WAX MATCH.

SPECIFICATION forming part of Letters Patent No. 684,997, dated January 1, 1901.

Application filed January 13, 1898. Serial No. 628,021. (No model.)

To all whom it may concern:

Be it known that I, ANDREW JOHN FREDRIKSON, manufacturer, a subject of the King of Sweden and Norway, residing at Jönköping, in the Kingdom of Sweden, have invented certain new and useful Improvements in the Manufacture of Wax Matches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention relates to improvements in wax matches, and more particularly to the preparation of wooden cores or splints for the same, and to provide the same with certain new and useful features, hereinafter more 20 fully described, and particularly pointed out in the claims.

Wax matches as heretofore made, having a core of yarn or fibrous material, have been found defective in that they are too flexible, 25 especially when anywise warm, and also require a large proportion of wax or fatty matter; also the cotton or other fibrous core does not burn freely and also gives off an objectionable odor.

30 Wax matches made with a round smooth core of wood coated with suitable wax are objectionable in that the wax does not sufficiently penetrate the fibers of the wood and is liable to become loosened therefrom and 35 also the wood burns too slowly and the wax is liable to melt near the burning end and drop off instead of burning as it should. Thus while furnishing a core of sufficient stability and stiffness the wood core for wax matches, 40 as heretofore made, fails of being satisfactory.

I have found that it is necessary in order to hold the melted wax and prevent its running back or dropping off the match that the core should be very open or porous, like a 45 sponge. In the case of cores made of yarn a number of strands arranged side by side are used. These tend by capillary attraction to hold a large amount of melted wax in the space between the strands. The object of my 50 invention is to so prepare these wood cores that the wax will penetrate them more freely

and adhere more closely thereto, so that said wood cores will burn more freely and at the same time retain the melted wax between the parted fibers thereof and retain the needed 55 strength and stability. I accomplish these results by separating and breaking apart or deeply creasing the outer fibers of the wood cores, while enough of the inner fibers of the wood remain unchanged to impart the necessary 60 strength and stiffness to the core, a way of so doing being illustrated in the accompanying drawings, in which—

Figure 1 is a perspective of a sheet of veneer after it has been treated by cutting-rolls, 65 as hereinafter specified; and Fig. 2, a match splint or core made from the same.

The breaking up and loosening or creasing of the fibers may be done mechanically in various ways. I do not claim to be limited 70 in this respect. A preferred way of so doing consists in passing sheets of veneer A between rolls having sharp cutting-ridges and preferably treating the veneer with these cutting-ridges diagonally to the grain in opposite directions, as shown at a', whereby the outer surface fibers of the veneer are cut and broken and materially loosened and made more absorbent and more readily consumed when lighted. These veneers are then cut 75 into short strips of suitable size to form cores B for wax matches and will then have a rough and broken-apart surface b b' and a compressed and unbroken interior. This broken and rough surface will now readily 80 absorb the wax coating and form a surface of such porosity and roughness that the wax will firmly adhere thereto when cold, and when ignited the separated particles of wood will burn more rapidly and fully and also retain the melted wax adjacent to the flame and 85 prevent its running back on the match or dropping off the same. I thus secure a very satisfactory result by means of my invention where previous attempts have been defective, 90 as heretofore stated. These cores are cheaper and lighter than those made of strands of 95 yarn, they require less wax, provide more burning material, furnish cores of sufficient stiffness without depending on the wax for the same, and do not give off any offensive odor when burning.

Having thus fully described my invention, what I claim, and desire to secure by Letters Patent, is—

1. The described wood core for wax matches, consisting of a strip of wood having its fibers mechanically loosened, or separated, to render the same more absorbent, and more easily consumed, substantially as described.
2. A wax match consisting of a core of wood having its outer portion mechanically loos-

ened and separated, a coating of wax on said core, and penetrating the same, and an igniting compound on the same, substantially as described.

In testimony whereof I affix my signature in presence of two witnesses.

ANDREW JOHN FREDRIKSON.

TH. WAWRINSKY.

Correction in Letters Patent No. 664,997.

It is hereby certified that in Letters Patent No. 664,997, granted January 1, 1901, upon the application of Andrew John Fredrickson, of Jönköping, Sweden, for an improvement in "Wax Matches," an error appears in the printed specification requiring correction, as follows: In the heading, date of filing application, the words and figures "Application filed January 13, 1898," should read *Application filed March 17, 1897*; and that the said Letters Patent should be read with this correction therein that the same may conform to the record of the case in the Patent Office.

Signed, countersigned, and sealed this 21st day of January, A. D., 1902.
